APPARATUS FOR STRAIGHTENING ARTICLES THAT SOFTEN UNDER HEAT

Harold H. Snyder, Mount Lebanon, and Samuel A. Forter, Avalon, Pa., assignors, by mesne assignments, to Giafent Corporation, a corporation of Maryland

Application March 24, 1942, Serial No. 435,974

9 Claims. (Cl. 49—58)

1

This invention is found in apparatus for straightening lengths of material normally rigid, but susceptible to softening by heat. It finds practical application in the production of glass rods and tubes, and consists in means for minutely straightening the article and rendering it fit for the market. The invention will ordinarily be practised upon the material when newly formed. Inherently, however, there is no necessary time relationship between the forming of the article and the straightening of it according to my present invention.

In the accompanying drawings Fig. I is a view partly in plan, partly in horizontal section of apparatus in which and in the operation of which my invention may be realized. Fig. II is a view in vertical and longitudinal section of the same apparatus, on the plane indicated at II—II, Fig. I. In Fig. II the broken line I—I indicates the plane of view of Fig. I, with these qualifications: the horizontal section given in the left-hand portion of Fig. I is really a view on two planes of section; the plane of section at the bottom of the figure is that indicated by the line I—I, Fig. II; the plane at the top of the figure is a plane immediately above the work-sustaining rolls. (Contrary to the impression that might be gained by a glance at Fig. I, the apparatus is, but for the driving mechanism, symmetrical with respect to a vertical and longitudinal mid-plane.) The other qualification is that, in the portion of Fig. I to the right, a flue shown in Fig. II has, for purposes of illustration, been shown to be broken away. Fig. III is a fragmentary view in vertical and transverse section, on the plane indicated at III—III, Fig. II. Fig. IV is a fragmentary view to larger scale on the transverse plane indicated at IV—IV, Fig. I. Fig. V is a view to like scale with Figs. I and II, showing fragmentarily in side elevation an element of structure detached. Fig. VI is a fragmentary view to like scale with Fig. IV, showing partly in elevation and partly in section an element that in Fig. IV is shown in elevation. Fig. VII is a view in section, on the plane indicated at VII—VII, Fig. VI. Fig. VIII is a fragmentary view on the plane indicated at VIII—VIII, Fig. VI. Fig. IX is an exploded view in side elevation of the element of Fig. VI. Fig. X is a view in elevation of the two link shapes that go to make up the conveyor chains.

In an application for Letters Patent of the United States, filed January 23, 1942, Serial No. 427,916, now Letters Patent No. 2,402,924, dated June 25, 1946, owned by the assignee of the in-

2

vention herein described, there is described apparatus for shaping glass rod and glass tubing in continuous length; and in an application filed September 29, 1941, Serial No. 412,788, now Letters Patent No. 2,306,721, dated December 29, 1942, we have described apparatus for cutting to definite length glass rod and tubing so continuously produced. The lengths of rod or of tubing, after they have been cut, still require minute straightening, before they are ready for the market; and it is with the straightening that our present invention has to do.

In the apparatus of the invention, the desired end is accomplished by causing the glass article, when resting by gravity tangentially upon the surfaces of two parallel and adjacently placed rolls, one of which and preferably both of which are in rotation to come to a temperature at which it loses its rigidity and becomes soft and slightly plastic; and, the rolls being straight, the softened article will under gravity straighten itself upon them. The operation is conveniently accomplished by causing the co-operating rolls and the article carried by them to advance through a furnace, and in the course of such advance first bringing the article from relatively cold and rigid state to a relatively hot and softened state, and then bringing it to cold and rigid state again.

As best seen in Fig. II, an endless conveyor 1, mounted on sprocket wheels 2, and driven by a motor 3, extends into, through, and beyond a furnace 4. The upper reach of the conveyor extends in horizontal plane, and forms the semblance of a floor—a moving floor of the heating chamber of the furnace. The conveyor is composed of rolls 5 (cf. Figs. IV and VI), rotatably mounted at their ends in the links 6 of parallel and spaced apart chains. The chains are engaged by the sprocket wheels 2, and thus the conveyor is driven. The assembled rolls at one end carry each a pinion 7; upon the furnace structure a rack 8 is mounted; and the interengagement of the pinions with the rack effects rotation of the rolls throughout the upper reach of the conveyor, as the conveyor advances. The rolls turn in uniform direction—clockwise, as seen in Fig. II. The direction of travel of the upper reach of the conveyor is, as seen in Fig. II, from left to right. At the intake end the pieces of work G are fed one by one, to rest upon and between each roll and the next roll to rearward; and at the exit end the pieces are delivered one by one to suitable receiving apparatus.

The desiderata that the invention contemplates are a furnace chamber that is tight, both to pre-

vent loss of heat and to protect against flame exteriorly arranged portions of the apparatus; and rolls that under varying temperature continue truly cylindrical, unbowed, and straight.

The furnace includes a fire-box of refractory material. Through the forward and rear end walls of this box (so characterized with reference to the line and direction of conveyor travel) are arranged burners 9; and through the side walls other burners 10. This fire-box, otherwise enclosed, has in its bottom wall a medial opening 11, through which the stream of flame and gas emerges, as indicated by the arrows, Fig. II, to play upon the conveyor and its burden midway of the upper reach, and to spread thence forwardly and rearwardly. At the intake and exit ends of the furnace the gaseous streams find exit through conductors 12 to a passageway 13 leading to a stack. Along the sides, however, the furnace encloses the ware-carrying portion of the conveyor, and the structure is illustrated in Figs. I and IV.

The refractory fire-box is provided along the sides with skirts formed of refractory blocks 14 that extend along the furnace and overhang at a narrow interval the ends of the rolls 5 of the conveyor. The furnace structure is carried upon uprights 15 that stand spaced at an interval from and on the two sides of the furnace; and upon interposed beams 16, 17, 18 these uprights carry castings 19 and channel lengths 20, 20 that form in effect continuations of the furnace walls downward to the real and rigid floor 21. These continuations of the furnace walls downward are, as will be seen, continuations with intervals of interruption between, and through the spaces that constitute the interruptions the conveyor extends. That is to say, the conveyor is wider than the furnace, and at its sides projects through spaces formed for it in the furnace walls.

The conveyor driving and the roll-rotating means are arranged externally of the furnace walls, and in the interval at which the uprights 15 stand spaced from the walls. More complete closure of the intervals in the walls is effected by plates 22, 23, bolted to place between the beams 16, 17, 18 and the walls. These plates define slots through which the ends of the rolls, reduced in size, extend.

The rolls are of compound structure. Each includes a body 5 that is merely a cylindrical shell, and spindles 24 (there is one at each end) that constitute axles. With these axles the cylindrical body 5 of the roll is connected in a union that provides for unity in rotation and relative movement telescopically in longitudinal direction. It is to the axle 24 that the rack-engaging pinion 7 is immediately secured, as by the pinned connection 70. The bodies 5 of the rolls are advantageously formed of heat-resisting steel-nickel-chromium steel, for example.

The spindles 24 serve as the axles of the rolls; they serve also as the pintles of the chains. The chains are made up of the alternate links 6 and 25. Each link 6 includes two cylindrical portions, adapted to be mounted with snug turning fit upon the spindles 24 of two succeeding rolls, and of an interconnecting web. The links 25 are simple plates perforated at their ends with properly spaced orifices of proper size, which in pairs are arranged between and by the spindles 24 articulated with succeeding links 6. The links 6, throughout the upper reach of the chain travel make engagement, as shown in Fig. VI, with rails 26, which in turn are mounted upon the

frame (as upon beams 16). Thus the conveyor is accurately positioned and guided.

To the spindle 24 at its inner end (the left-hand end, Fig. VI) a sleeve 27 is secured by the pin 28. Upon the spindles 24 of succeeding pairs of rolls plates 29 are strung. In the assembly the plates 29 lie snug in face-to-face contact with the inner faces of plates 22, 23; and in snug end-to-end succession, effecting a substantially complete closure. The plates 29 are rounded at their corners, as shown in Fig. VIII, to allow the assembly freely to round the sprocket wheels.

The sleeve 27, minutely shaped for the purpose, affords proper support for the coaxial assembly 15 of roll and axle, and baring for relative telescopic movement of the parts. Slots 30 in the sleeve, engaged by the ends of the pin 28 afford union in rotation. The plates 29 are held to snug abutment upon the inner faces of plates 22, 23 by the pinned-together assembly shown in Fig. VI. This pinned-together assembly engages oppositely the rigidly mounted parts 22, 23, on the one hand, and the rail 26, on the other.

The structure shown in Fig. VI may be understood to be duplicated at the opposite end of the roll, with the qualification that the pinion 7 and the rack 8 will conveniently not be duplicated. A single drive suffices for roll rotation.

The fire box in details of structure is illustrated in Figs. I-III. It is, as has been said, a refractory-walled chamber with burners 9 and 10 in end walls 9a and side walls 10a and a flame-delivery orifice 11 arranged medially in its nether wall. The refractory walls are faced with insulating brick, as indicated at 30. In over-all shape the fire box is rectangular, of greater length than width, and of greater width than depth. Within the rectangular space tunnels 31 are formed. They extend from the end walls toward the medial portion of the fire box, but do not extend to the centre; they leave the space within the fire box free and unobstructed in its medial portion. The tunnels are triangular in cross section, and the floors 32 of these triangular tunnels form the bottom wall of the fire box and define the orifice 11. The tunnels 31 correspond in number to the burners 9 in the end walls of the fire box, and into them the burners severally deliver their flames. It is into the free medial space within the fire box that the burners 10 in the side walls are directed. The roof of the fire box above this space is more heavily insulated, as indicated at 33, and from this space the flames have exit through the orifice 11 in the bottom wall of the fire box.

Flames spring from the burners 9 in the end walls and flow through the tunnels 31 to the medial space within the fire box. Additional flames spring from the side walls of this medial space. The united streams of flames emerge downwardly through the fire box opening 11 and spread upon the conveyor that carries the work in rotation upon it. From this central portion the flame spreads and flows forwardly and rearwardly over the conveyor and beneath the tunnel floors 32 to the end exits already described. Dampers 34 set in the conductors 12 may be adjusted to afford the desired condition of flow of the gaseous streams both in their actual and relative volumes over the conveyor. The floors 32 of the tunnels, flowed over by streams of flames both above and beneath are merely definitive of stream flow. There is small heat transference through them; and, whatever there may be, the

transfer is to another portion of the stream, so that there is no loss.

The peak temperature is substantially at the mid point in the length of the furnace. To that peak there is rise from the intake end; and from it there is descent to the exit. The peak temperature will be that at which the glass softens; it will be less than that at which the glass melts.

The motor 3 that drives the sprocket wheels and effects conveyor travel is advantageously a D. C. motor, and is energized from a squirrel-cage generator 35. The generator in turn is driven by an A. C. motor that is supplied from the usual electric supply line. By such provision constancy of speed of conveyor travel may be maintained, undisturbed by variations of current in the supply line.

In this furnace, by proper control of the burners and of the speed of conveyor travel we establish and maintain with uniformity heat conditions such as to bring the articles under treatment from room temperature to the desired peak and to allow them to cool again to a temperature at which they have become rigid, and to a temperature at which they may safely be returned to the open air.

It is manifest that the essential characteristic of the material to which the apparatus is adapted is that it, normally rigid, softens under elevated temperature. Glass is typically such a material, and operation upon glass articles has here been described; but, manifestly, apparatus identically that shown and described, with adaptation in temperature of operation, is applicable generally to articles having the physical characteristic here named. To articles of resin, for example.

We claim as our invention:

1. In apparatus comprising a furnace including an endless traveling conveyor having upper and lower reaches interconnected in rounded courses at their opposite ends and the upper reach extending through the furnace and providing a work-support; the invention herein described which comprises a fire box arranged at an interval above the conveyor and extending longitudinally of the conveyor and provided medially in its lower wall with an opening, means including burners directed through the opposite end walls of said fire box for directing streams of burning fuel and hot gases from opposite ends through the fire box and through the opening in the lower wall thereof and causing the flames and hot gases to spread thence in opposite directions in the interval between the conveyor and the fire box, and outlets arranged adjacent to, and external of, the opposite ends of the fire box for the escape of hot gases flowing in opposite directions through said interval between the fire box and the upper reach of the conveyor.

2. The structure of claim 1, the fire box being provided interiorly with tunnels that extend from the end walls to said opening, and said burners leading through the end walls of the fire box to the tunnels severally.

3. The structure of claim 1, the fire box being provided interiorly with tunnels that extend from the end walls to said opening, and said burners leading through the end walls of the fire box to the tunnels severally, the floors of the tunnels constituting partitions over which above and below the hot gas flows oppositely.

4. The structure of claim 1, the fire box being provided interiorly with tunnels that extend from the end walls to said opening, and said burners

leading through the end walls of the fire box to the tunnels severally, together with burners in the side walls of the fire box leading to the mid portion thereof.

5. In apparatus for straightening lengths of glass that includes a furnace, a conveyor consisting of a pair of sprocket-driven endless chains and rolls rotatably mounted on the chains movable through the furnace, and means for rotating the rolls in response to conveyor travel, the invention herein described which consists in compound rolls that include each a cylindrical body and an axle, the cylindrical body being secured for rotation with but being movable axially of said axle, the furnace wall being slotted and the roll axle in the assembly extending through the slot, a sleeve secured to the axle and adapted to sustain outward thrust, a pinion secured to the axle and adapted to sustain inward thrust, slot-closing plates borne by the axles of the rolls and held to slot-closing position between sleeve and pinion.

6. In apparatus for treating glass articles that includes a furnace, and a conveyor for moving the articles through the furnace, the invention herein described which consists of a fire box arranged at an interval above the conveyor and extending longitudinally of the conveyor, the fire box being provided interiorly with tunnels that extend from the end walls toward but terminating short of the middle of the fire box leaving an unobstructed mid portion, and with burner orifices leading through the end walls of the fire box to the tunnels severally.

7. In a furnace having side walls formed with longitudinally extending slots, and an endless traveling conveyor having upper and lower reaches interconnected in rounded courses at their opposite ends, the upper reach of said endless conveyor extending through the furnace and providing a work-support which extends at its opposite sides outward through said slots in the furnace side walls; the invention herein described comprising a succession of shields articulated to the opposite sides of said conveyor for angular movement relatively to one another as the conveyor advances through said rounded courses, said shields being adapted to move into alignment as the conveyor advances into and through said upper reach and cooperating with one another to form substantially continuous baffles that screen said slots in the furnace side walls.

8. In a furnace having a side wall formed with a longitudinally extending slot, and an endless traveling conveyor having upper and lower reaches interconnected in rounded courses at their opposite ends, the upper reach of the said conveyor extending through the furnace and providing a work-support which extends on one side outward through said slot in the furnace side wall; the invention herein described comprising a succession of shields articulated to said side of the conveyor for angular movement relatively to one another as the conveyor advances through said rounded courses, said shields being adapted to move into alignment as the conveyor advances into and through said upper reach and cooperating with one another to form a substantially continuous baffle that screens said slot in the furnace side wall.

9. In apparatus of the class described comprising a furnace including means for supporting work to be heated, and a fire box having end walls, said fire box being arranged above said work-supporting means; the invention herein described

wherein said fire box extends longitudinally of the work-supporting means and includes tunnels that extend from the end walls toward but terminate short of the middle of the fire box leaving an open mid-portion in the fire box above said work-supporting means, and burner orifices leading through the end walls of the fire box to the tunnels severally.
